UNITED STATES PATENT OFFICE.

HOWARD C. McDONALD, OF BUFFALO, NEW YORK.

TOWEL HOLDER OR DEVICE.

1,323,296.

Specification of Letters Patent.

Patented Dec. 2, 1919.

Application filed January 26, 1917. Serial No. 144,741.

To all whom it may concern:

Be it known that I, HOWARD C. McDONALD, a citizen of the United States, residing at Buffalo, in the county of Erie and State 5 of New York, have invented a new and useful Improvement in Towel Holders or Devices, of which the following is a specification.

This invention relates to a towel holder 10 or device suitable for use in lavatories and other more or less public places, for enabling persons to have the use of individual towels which are locked or secured so as to prevent the theft or misuse of the towels.

15 Numerous attempts have been made to produce a towel holder or delivery device of this nature but these prior devices have been found impractical or undesirable for one or another reason. It is necessary to 20 lock or secure the towels to prevent them from being stolen and misused, but this should be accomplished in such a way as to enable the ready and convenient use of the towels, and also to enable the towels to be 25 removed from the holder or device and replenished by the towel supply man expeditiously and with the minimum labor and handling of the towels. It is also obligatory 30 to observe sanitary precautions by preventing the contact of the soiled or used towels with the clean or unused towels. The persons ordinarily making use of such towel 35 holders or devices will operate the device to obtain a towel for use but when through 40 with the towel will drop the same in the easiest way possible and cannot be relied upon to take any pains to see that the soiled towel enters the intended receptacle or is otherwise disposed of in the manner intended to preserve the neat appearance of 45 the device. If, therefore, a tidy appearance of the towel holder or device is to be preserved it is necessary to make provision for a suitable disposition of the soiled towels without relying upon the users to make any effort in this direction.

The objects of the invention are to produce a practical and desirable towel holder 50 or device which, while affording ready use of individual towels, prevents the theft or misuse of the same, is thoroughly sanitary, and insures such a disposition of the soiled towels that they are always hidden from sight without requiring the user, after using 55 a towel, to do anything but to merely drop or release the used towel; also to provide a

towel holder or device having operating means, capable of ready and easy operation, by the actuation of which a person desiring to use a towel obtains access to the same 60 and by this act moves the previously used towel to a position where it is out of sight and does not interfere with the use of the clean towels; also to provide a towel holder or device in which a supply of clean towels 65 can be placed in position and the soiled towels removed with the minimum expenditure of time and labor in handling and replenishing the towels; also to provide a towel holder or device in which the towels are 70 folded and retained in a novel manner which facilitates the insertion and removal of the supply of towels and also the ready use of the towels by the individual users.

In the accompanying drawings:

75 Figure 1 is a sectional elevation of a towel holder embodying the invention, showing the normal position of the parts.

Fig. 2 is a similar view showing the position of the parts when the door is opened 80 to obtain a towel.

Fig. 3 is a front elevation on a reduced scale thereof.

Fig. 4 is a transverse sectional elevation 85 of the casing showing the towel-operating mechanism in elevation therein, a portion of the door of the casing being broken away to disclose the parts in rear of the same.

Fig. 5 is an end elevation of a pack or bundle of towels ready for insertion into 90 the casing.

Fig. 6 is a fragmentary perspective view 95 of the rear separating plate used between the soiled and clean towels, and its holder.

Fig. 7 is an enlarged fragmentary sec- 95 tional elevation of the towel clamp or locking device.

Fig. 8 is an elevation, partly in section, 100 of the means for locking the towel clamp in the casing.

Fig. 9 is an edge view of a towel showing the manner in which the towels are folded.

1 represents a casing which may be of any suitable form and construction, the casing being preferably made of sheet metal 105 and of a form and size adapted to stand upright upon the floor. The casing is provided at its front with a door opening 2 through which access is had to the towels in the casing, and 3 is a door for closing 110 this opening. Preferably the door is arranged to slide vertically in suitable guides

4 at the opposite sides of the casing and is adapted to be opened by a treadle 5 suitably connected to the door. As shown, the treadle extends through an opening in the lower 5 part of the casing, is hinged at its front, and is connected at its rear end to a cord or flexible connection 7 which is wound around and attached to a small pulley 8, suitably journaled in the rear portion of the 10 casing. This pulley 8 is formed with or secured to a large wheel or pulley 9 to which is attached one end of a cord or flexible connection 10 which extends up through the casing, passes over guide pulleys 11 and 15 12 in the upper portion thereof and is suitably attached at its opposite end to the sliding door 3. When the treadle is depressed the pulleys 8 and 9 are rotated and the cord 10 is wound on the grooved periphery of the large pulley 9, thereby raising the door, as shown in Fig. 2. When the treadle is released the door will descend by gravity, winding the cord 7 on the small pulley 8 and raising the treadle ready for 20 the next actuation. Any other suitable means adapted to be readily operated by a person desiring to use a towel can be employed for opening the door 3.

13 represents a pack or bundle of towels 30 which are locked between their ends in a clamp or holder 14 mounted and locked in the casing 1. The towels hang from the clamp or holder in the casing in rear of the door opening 2, as clearly shown in Figs. 35 1 and 2, where they can be reached and drawn out through the opening 2 far enough for use, but the towels cannot be detached and removed except by unlocking the clamp. Each towel is folded as shown in Fig. 9, 40 that is, the opposite ends of each towel are folded over to opposite sides so that when the towels are suspended from their middle portions by the clamp, both folded ends of each towel will extend upwardly at the front 45 side of the towel. In this way the folded end of the front or outermost towel of the pack can be readily grasped and the towel pulled forwardly through the opening 2 in the casing. The towels shown are of such 50 length that one-half of each double towel is sufficient for ordinary use and only one-half of a towel is used at one time. While the double towels shown are preferably employed, since they can be laundried and 55 handled more economically, it should be understood that separate towels, each of substantially half the length of the towels shown could be used and secured by their upper ends in the clamp 14 with their depending lower ends folded upwardly and 60 forwardly in the manner explained, without altering the principle or operation of the towel holder or device, and hereafter, in this specification, a half of each double 65 towel is referred to as a towel. In the

use of the device, after each towel has been used, it is carried upwardly and over to the rear of the pack of towels as herein-after explained, leaving a fresh towel ready for the next user, and there is always presented at the front of the pack of towels, even when the front halves of all of the towels have been used, an upwardly and forwardly extending folded end ready to be grasped and pulled forwardly through the 75 opening 2 in the front of the casing.

The towel clamp or locking device may be of any suitable construction adapted to secure the pack of towels together and suspend them locked in the casing. The clamp 80 shown consists of a roller or rod 15 and a parallel channel-shaped bar 16 between which the towels are clamped. The clamping bar 16 is movable toward and from the roller 15 on eye bolts 17, the eyes of which 85 encircle the roller 15 and the shanks of which pass through holes in the ends of the clamping bar. Nuts 18 having operating handles 19 are screwed on the bolts 17 and by screwing down these nuts the clamping 90 bar is forced toward the roller or bar 15 to tightly grip and secure the pack of towels between the two bars. When the handles 18 of the nuts are turned to a position in which they extend inwardly toward each 95 other, as shown in Fig. 4, they are locked by a padlock or other device 20 engaged in holes in the ends of the handles, and the towels cannot then be removed from the clamp without unlocking and unscrewing 100 the clamping nuts 18. One of the clamp bars, for instance the roller 15, is preferably provided at its ends with journals 21 adapted to rest in suitable bearings 22 and 23 in the opposite sides of the casing, so as 105 to permit the clamp to rock or tilt in its bearings. The clamp can be locked in its bearing to prevent the unauthorized removal of the pack of towels in any suitable manner, for instance, one journal of the 110 clamp is inserted endwise in a hole in the bearing 22 and the other journal is dropped into an open slot 24 in the bearing 23 and locked therein by a pad-lock 25, the bail of 115 which is passed through perforated lugs on the bearing 23 above the journal 21.

The towels can be secured in the clamp at the toilet supply house or laundry and brought to the towel holder ready for insertion therein. The folded ends of the 120 towels can be temporarily tied with a string 26, as shown in Fig. 5, or otherwise bound together to prevent them from becoming unfolded in handling the towels. When the towels have been placed in position in the 125 casing their folded lower ends are confined between front and rear partitions or plates 27 and 28, and the string or temporary binder is removed to permit the use of the towels. The front plate 27 is hung in the 130

casing on a cross rod 29, or is otherwise suitably supported with its upper edge located so that the folded end of the front towel projects forwardly over the plate, as shown in Figs. 1 and 2, and can be readily grasped to pull the towel forwardly through the access opening. The rear partition or plate 28 is preferably pivotally suspended at its upper edge on a rod or bail 30, having 5 crank arms 31 at its ends provided with outwardly projecting journals 32 which enter and are adapted to rock in bearing holes in the sides of the casing. This rear plate 28 hangs loosely against the rear side of the pack of towels and is adapted to follow 10 forwardly with the pack as the towels are used, always bearing against the rear towel of the pack and pressing the pack forwardly against the front plate 27. Thus, notwithstanding 15 standing the diminishing thickness of the pack of towels, their lower folded ends will always be properly held between the two partitions or plates.

33 represent two endless chains which are 20 arranged in the casing 1 at opposite sides thereof, and are connected by rods 34 forming an endless carrier. Each chain passes around chain wheels 35, 36 journaled in any suitable manner respectively in the upper 25 and lower portions of the casing. The endless carrier is adapted to be operated each time the door 3 is opened to cause one of the rods 34 thereof to move upwardly in the casing in front of the pack of towels. When 30 a person desires to use a towel he opens the door 3 by the operation of the treadle 5, as explained, and draws the front towel of the pack forwardly through the door opening 2. When the towel is dropped after use, it will 35 swing downwardly and inwardly through the door opening 2 into the casing and hang therein, as shown in Fig. 1, with the lower end of the towel resting against the front side of one of the rods 34 of the carrier. This rod holds the soiled towel out of contact with the pack of clean towels and thus prevents possible infection by contact of a soiled towel with a clean towel. It is not necessary for the user of a towel to take 45 any precaution as to the disposition of the soiled towel. If he simply drops the towel, as the ordinary user does, the towel will naturally fall by gravity into the position shown in Fig. 1, with its lower end hanging 50 against the cross rod 34. When the user removes his foot from the treadle 5, the door 3 will descend by gravity and hide the soiled towel. The soiled towels therefore are not exposed and do not cause an 55 untidy appearance of the device. When the door is again opened by the next person desiring to use a towel, the endless carrier will be moved a step, and the rod will carry the soiled towel up to the position above the 60 pack of clean towels, indicated in Figs. 1

and 2. At the next operation of the carrier this towel will be moved downwardly in rear of the pack of towels and at the rear side of the rear partition plate 28, as shown in Fig. 2, and the next soiled towel will be 70 carried up as explained, the soiled towels being thus carried in succession to the rear of the pack.

The endless carrier can be operated to thus dispose of the soiled towels by any suitable mechanism which will cause the carrier to move one step each time the door 3 is opened. In the construction shown, the door is provided at its lower end with fingers 38 which are adapted to engage studs or projections 39 on the chains 33 and move the front runs of the chains upwardly when the door is raised. These studs or projections 39 are arranged at such intervals that each time the door is lowered its fingers 38 will engage under one pair of the studs 39, as shown in Fig. 1, in position to move the carrier when the door is next raised. In order to prevent the carrier from overrunning and turning backwardly, a stop lever or 90 device 40 and a dog 41 are shown. The stop lever 40 is pivoted in the lower portion of the casing and is provided with an arm having a lateral projection 42 adapted to be struck by the treadle when the latter is depressed, 95 and an arm 43 adapted to move into the path of the cross rods 34 of the carrier to limit the movement of the chains. When the treadle is depressed and strikes the lower arm 42, the lever will be swung to the position indicated in Fig. 2 and will intercept one of the cross rods, thereby arresting the carrier in position for the fingers 38 on the door to properly engage one pair of studs 39 on the chains. When the treadle is released, the stop lever 40 is adapted to swing out of the path of the rod 34 to a position to permit the movement of the carrier at the 100 next operation of the treadle. A spring 44 is shown attached to the stop lever and to the front wall of the casing for retracting the stop lever. This spring, however, is not absolutely essential as the stop lever can be weighted so as to swing back to its normal position by gravity, or the cross rods of the 115 carrier can be relied upon to move the stop lever back out of the way when the carrier is moved. The dog 41 shown consists of a pivoted bar adapted to swing by gravity into engagement with the teeth of the lower 120 sprocket wheels to prevent backward movement of the wheels and endless carrier. Thus the stop lever 40 prevents the overrunning or over forward movement of the carrier and the dog 41 prevents the backward 125 movement thereof, these parts coöperating to insure the exact movements of the endless carrier.

The soiled towels when hanging down at the front of the pack are held out of contact 130

with the clean towels by the rods 34 of the carrier, and the soiled towels at the rear of the pack are separated from the clean towels by the rear partition plate 28. There is therefore no danger of contamination or infection by contact at any time of the soiled and clean towels. As the towels are carried over from the front to the rear of the pack one after another in the operation of the device, the clamp 14 will gradually turn in its bearings, due to the shifting of the weight, thereby causing the soiled towels to hang properly at the rear of the pack and preventing them from bunching up at the top of the pack and possibly falling down in the way in front of the clean towels, and interfering with the proper operation of the device. The towel holder or device is adapted both for use in the manner described in places where it is intended to furnish towels for use free of charge, and also for use with a coin-controlled attachment or mechanism which will prevent one from obtaining access to or the use of a towel without first depositing a suitable coin to release the door 3, treadle 5 or other part of the operating mechanism. Since, however, the coin-controlled mechanism does not form a part of this invention it is not herein shown or described.

I claim as my invention:

1. In a towel holder, the combination of a pack of towels secured in the holder so as to enable the individual use of the towels and to permit a used towel to hang with a part thereof free, an operable mechanism comprising a member which moves relatively to the pack to carry said hanging used towel to a different position where it is out of view and does not obstruct access to said pack of towels.

2. In a towel holder, the combination of a pack of towels secured to permit a used towel to hang with one end free from the front of the pack, and mechanism operable by the user which has a part that moves upwardly in front of the pack of towels and carries said hanging used towel over to a position at the rear of the pack.

3. In a towel holder, the combination of a pack of towels secured together in position to permit a used towel to hang with one end free, and towel operating mechanism comprising a carrier arranged to pass around the pack of towels and carry said hanging used towel to a position out of view.

4. In a towel holder, the combination of a pack of towels secured to permit individual use of the towels, and towel operating mechanism comprising rods arranged to travel upwardly and downwardly around the pack of towels and against which used towels are adapted to hang, said used towels being carried to the rear of the pack by said rods.

5. In a towel holder, the combination of a pack of towels secured to permit individual use of the towels, and towel operating mechanism comprising an endless carrier arranged to travel upwardly and downwardly around the pack of towels and having horizontal rods against which used towels are adapted to hang at the front of the pack, said used towels being carried to the rear of the pack by said rods.

6. In a towel holder, the combination of a pack of towels, means for securing said towels with their ends hanging, an endless carrier arranged to travel upwardly in front of and downwardly in rear of the pack of towels and having horizontal rods against which used towels are adapted to hang at the front of the pack, said used towels being carried to the rear of the pack by the upward travel of said rods.

7. In a towel holder, the combination of a pack of towels secured to permit a used towel to hang with one end free, means inclosing the towels, means operable to afford access to the towels, and mechanism actuated upon the operation of said access-affording means which carries said hanging used towel to a position out of view.

8. In a towel holder, the combination of a pack of towels secured to permit a used towel to hang with one end free at the front of the pack, means inclosing the towels, means operable to afford access to the towels, and mechanism actuated upon the operation of said access-affording means which carries said hanging used towel over to a position at the rear of the pack.

9. In a towel holder, the combination of a pack of towels secured to permit a used towel to hang with one end free at the front of the pack, a casing inclosing the towels and having a door in front of the towels adapted to be opened to afford access to the towels, and mechanism actuated by the door upon the opening of said door which carries said hanging used towel over to a position at the rear of the pack.

10. In a towel holder, the combination of a pack of towels secured to permit a used towel to hang with one end free at the front of the pack, a casing inclosing the towels and having a door in front of the towels adapted to be opened to afford access to the towels, an endless carrier arranged to travel upwardly and downwardly around the pack of towels and having horizontal rods against which used towels are adapted to hang at the front of the pack, said used towels being carried to the rear of the pack by said rods.

11. In a towel holder, the combination of a pack of towels secured to permit a used towel to hang with one end free at the front of the pack, mechanism which is operable to carry said used towel over to a position

at the rear of the pack, and means for preventing contact of the used towel with the clean towels.

12. In a towel holder, the combination of 5 a pack of towels secured to permit a used towel to hang with one end free at the front of the pack, mechanism which is operable to carry said used towel over to a position at the rear of the pack, and a plate which 10 separates the used towels at the rear of the pack from the clean towels while permitting the used towels to remain attached to the pack.

13. In a towel holder, the combination of 15 a pack of towels, means for securing the towels between their ends to form substantially equal towel portions, said portions depending from said securing means and having their ends folded upwardly and forwardly, and means for retaining said towel portions in the folded condition with the extremities of the upwardly folded ends exposed in position for use, said securing means being so mounted as to allow each 20 of the depending towel portions when used, to be passed over said securing means to the rear of the pack.

14. In a towel holder, the combination of a pack of towels, means for securing the

towels with their ends hanging, the hanging 30 ends of the towels being folded upwardly and forwardly, a retainer against which the folded ends of the towels rest with their extremities exposed, and a plate which is pivoted in the towel holder and which hangs 35 loosely against the pack of towels and holds by its own weight the folded ends of the towels against said retainer.

15. In a towel holder, the combination of a pack of towels secured to permit individual 40 use of the towels, and towel operating mechanism comprising an endless carrier arranged to travel upwardly and downwardly around the pack of towels and having horizontal rods against which used 45 towels are adapted to hang at the front of the pack, means for actuating said carrier whereby the used towels are carried to the rear of the pack by said rods, and stop means for limiting the movement of said 50 carrier and preventing it from over-running.

Witness my hand this 24th day of January, 1917.

HOWARD C. McDONALD.
